CLAIM

The ornamental design for combined flowmeter rack and flow meters, as shown and described.

DESCRIPTION

FIG. 1 is a front perspective view of combined flowmeter rack and flow meters embodying the new design;

FIG. 2 is a back perspective view of the design shown in FIG. 1;

FIG. 3 is a front view of the design shown in FIG. 1;

FIG. 4 is a back view of the design shown in FIG. 1;

FIG. 5 is a right side view of the design shown in FIG. 1;

FIG. 6 is a left side view of the design shown in FIG. 1; and,

FIG. 7 is an exploded view of the design shown in FIG. 1, with the combined flowmeter rack and flow meters shown separately from a flowmeter rack.
